TRAILER COACH

Rex R. Anderson and Wayne G. Miller,
Pinconning, Mich.

Application June 23, 1952, Serial No. 20,320

Term of patent 14 years

(Cl. D14—3)

To all whom it may concern:

Be it known that we, Rex R. Anderson and Wayne G. Miller, both citizens of the United States of America and both residing at Pinconning, Michigan, have invented a new, original, and ornamental Design for a Trailer Coach, of which the following is a specification, reference being had to the accompanying drawings, forming a part hereof.

Fig. 1 is a perspective view of a trailer coach embodying our new design;

Fig. 2 is a perspective view thereof taken opposite Fig. 1;

Fig. 3 is another perspective view thereof with a portion broken away to show the interior; and

Fig. 4 is a similar view taken from the front corner opposite the view of Fig. 3.

The dominant feature of our design resides in the portion disclosed in full lines.

We claim:

The ornamental design for a trailer coach, substantially as shown and described.
